TENT

Verne Anderson and Charles Anderson,
Muskegon, Mich.

Application March 14, 1942, Serial No. 434,744

7 Claims. (Cl. 135—1)

This invention relates to tents. While it is fully appreciated that special purpose tents have heretofore been proposed for varied uses and hence embody various structural details in accordance with such uses, it has nevertheless been found that such special purpose tents have not heretofore successfully fulfilled the maximum requirements from the standpoint of simplicity, rigidity, comfort, and ease of setting up and taking down, as well as economy of manufacture.

This is particularly true of tents adapted for use as shanties, beach and actors location dressing quarters, and the like, where the time required to set the tents up and take them down is an important consideration in that these tents may be used only for a relatively short period, at any one particular time or place, and must be sturdy, comfortable and readily accessible. It is accordingly a primary object of this invention to provide a unitary collapsible tent which is capable of being erected without accessories for use, and collapsed for storage or transportation, in the minimum of time and in the minimum of space.

A further object of the invention is the provision of a collapsible tent of unitary construction whereby it is adapted for expeditious erection without the common use of poles, stakes, ropes, and the like.

A still further object of the invention is the provision of a unitary collapsible tent embodying a plurality of like sections and the sections being independently collapsible, whereby the tent as a whole is capable of being opened or extended to a variable extent and shape without impairing the stability thereof.

A still further object of the invention is the provision of a unitary collapsible tent which provides a weather tight compartment while at the same time providing means for sufficient ventilation to counteract possible foul air within such compartment.

A still further object of the invention is the provision of a unitary collapsible tent which is simple in construction, durable, comfortable in use, and which is capable of being manufactured at relatively low cost.

Other objects of the invention will be apparent to those skilled in the art to which our invention appertains.

Our invention is fully disclosed in the following description taken in connection with the accompanying drawings, wherein:

Figure 1 is a perspective view of the improved

tent showing same in erected and fully closed position;

Fig. 2 is a bottom plan view of the tent in the closed position of Fig. 1;

Fig. 3 is a perspective view of the tent in a normally wide opened position;

Fig. 4 is a view similar to Fig. 3 showing the tent in an abnormally wide opened position and with the rear sections partially collapsed;

Fig. 5 is a plan view of one of the fabric sections of which the body of the tent is constructed;

Fig. 6 is a plan view of the top fabric section of the tent;

Fig. 7 is a sectional view as observed in the plane of line 7—7 Fig. 1;

Fig. 8 is a sectional view as observed in the plane of line 8—8 of Fig. 1;

Fig. 9 is a sectional view as observed in the plane of line 9—9, Fig. 1;

Fig. 10 is a fragmental elevational view showing the means for holding and collapsing the fabric sections;

Fig. 11 is a view showing the tent as it appears in completely collapsed position.

Referring now in detail to the drawings, T designates the improved tent in its entirety. The tent T comprises a wall composed of a plurality of fabric sections 10 which may be variable in number and which are substantially of the form shown in Fig. 5.

The opposed longitudinal edges of the section 10 are retained between mating yieldable slats 11 and 12 which may advantageously be formed of wood and the adjacent edges of the sections 10 are disposed in lapped relation between the mating slats as indicated in Figs. 8 and 9.

In the construction of the tent, the lapped edges of the wall sections are preferably secured to corresponding ones of the mating slats as by staples indicated at 13 in Fig. 8 and thereafter the other corresponding ones of the mating slats are secured to the first ones as by nails 14, indicated also in Fig. 8.

The mating slats 11 and 12 provide in effect a flexible and yieldable framework composed of ribs, and the fabric sections connected therewith, as disclosed combine to provide a very sturdy unitary and self supporting structure.

The top of this unitary structure and its framework is further connected by marginal portions of a circular fabric section 15, which marginal portions are defined by an annular series of radial slits 16. By reference to Figs. 1, 2, 7 and 9, it will be seen that the edges of these slits are also disposed between the mating slats 11 and 12 and

overlay the lapped side fabric wall sections 10. These marginal portions of section 15 are thus connected and retained by certain of the staples 13 which pass through the matting slats, so that the substantially circular control portion of the section 15 extends transversely between each of the upper ends of the fabric sections 10, with the marginal portions depending loosely over each tent wall section between the radial slats or ribs of the framework. The fabric section 15 thus provides a closure for the top of the tent and a means for connecting the wall sections and slats in required circular spaced arrangement at the upper end of the tent structure.

The ribs or inner slat sections 12 are interconnected by a horizontal series of toggle levers 17, each of which comprises arms 18 and 19 having their opposed ends pivotally connected with adjacent ribs at 20 and their adjacent ends pivotally connected at 21. The arms 18 are provided with stops 22 to limit the movement of the arms to a horizontal position.

In the complete, normally erected position of the tent, the arms of the toggle levers are all normally in closed or horizontal position as illustrated in Figs. 1 and 2, thereby bowing the ribs and distending the fabric sections 10 in a somewhat "umbrella" fashion, the tent being of a form to provide maximum standing space therewithin and rigidity due to the shape of the connected fabric sections 10 and ribs.

The sections are preferably formed with extensions 24 at the base thereof for effecting a substantially weather-tight connection with the ground even if the tent be erected upon a somewhat irregular surface.

The top or closure section 15 while providing a weather-tight cover, nevertheless further provides for ventilation of the compartment within the tent due to the louver-like spaces 25 provided between the loosely depending marginal portions of the top section 15 and the side wall sections 10 and between the slots 16 as shown in Figs. 1 and 7.

The fabric sections 10 and 15 may be of any desirable material such as duck, canvas or other weather resisting material. It will be readily appreciated from the foregoing that the tent is unitary in structure and does not require the usual poles, stakes, guy ropes and the like to retain it in desired erected positions, it being only necessary to straighten the toggle links 17, as indicated in Fig. 2, whereupon the fabric sections are tensioned with a resulting bow to the normally straight ribs or slats 11, 12, and by the further provision of the base fabric extensions 24, the tent will rest in a stable position on substantially uneven supporting surfaces.

By the provision of toggle levers 17 individual to the different sections 10, all of which sections are connected at their upper ends by the circular fabric section 15 and by the elimination of any connection between two adjacent ribs, the tent may be opened to a variable extent as shown in Fig. 3, or may be further opened to a relatively larger extent, without seriously affecting the stability thereof as shown in Fig. 4.

As indicated in Fig. 3, the adjacent non-attached opening ribs or slats 11a are separated substantially 180° at their lower ends as a result of partially collapsing the toggle levers in the front sections adjacent such ribs. At this point it is to be particularly noted that the top section 15 retains all of the ribs against undue separation at their upper ends.

In Fig. 4, the adjacent non-attached ribs 11a are more widely spread at their lower ends, than is illustrated in Fig. 3, and several of the rear-most toggle levers are shown partially collapsed whereby the tent is not only opened to a greater extent than normal but the tent in its entirety is substantially collapsed, showing the stability of the structure.

Thus collapsing some of the toggle lever connections between the ribs provides for greatly varying the size of the door or passageway as well as various arrangements of the tent wall while some of the connections still remain in a stable supporting position.

When it is desired to transport or store the tent, it can be expeditiously collapsed without the separation of parts into a relatively small bundle, as indicated in Fig. 11.

It should be readily appreciated from the above disclosure that the improved tent is well suited for use as ice shanties, beach dressing rooms and the like or in any circumstances where use of an enclosure is desired only for a relatively short period of time, in that it is capable of being erected and collapsed in the minimum of time.

While we have disclosed but a single specific embodiment of our invention, same is to be considered as illustrative only, and not restrictive, the scope of the invention being defined in the subjoined claims.

What we claim and desire to secure by United States Letters Patent is:

1. A unitary collapsible tent having a frame comprising a plurality of normally straight flexible ribs, a fabric side wall member interconnecting said ribs for movement into adjacency in the collapsed position of the tent and into uniform spaced relation in the erected position thereof, with the ribs of said frame spaced throughout their lengths, a fabric top section also connected to said ribs and over-laying intermediate portions of said side wall member, the ends of two of said ribs being connected in adjacent relation by said top and laterally separable therebeyond to provide a passageway, and toggle link connections between each other two adjacent ribs intermediate the ends thereof for separating the ribs and tensioning the fabric side wall and for permitting collapsing of the tent.

2. A unitary collapsible tent according to claim 1, together with a top fabric cover having depending marginal portions interconnecting the upper ends of the ribs and loosely overlaying the side wall member between the ribs for admitting air to ventilate the interior of the tent.

3. A unitary collapsible tent according to claim 1, wherein said side wall member is provided with flexible extensions between each pair of ribs at the base of the tent, for providing a weather-tight connection with an irregular supporting surface.

4. A unitary collapsible tent comprising in the erected position thereof, a plurality of spaced bowed flexible ribs substantially widely spaced at the base of the tent and substantially closely spaced at the top of the tent, a pair of said ribs being free for opening and closing of the tent, a fabric side wall interconnecting the ribs, toggle link connections between the ribs and operable to hold the same in spaced relation and with the fabric side wall under tension, and a circular fabric top section having its marginal portion connecting one end of each of said ribs in circular arrangement, said toggle link connections be-

ing operable to collapse the tent with said ribs disposed in straight parallel relation.

5. A unitary collapsible tent according to claim 4, wherein said fabric side wall comprises a plurality of sections and wherein said ribs comprise mating slats with the upright edges of said sections secured between said slats in overlapped relation.

6. A unitary collapsible tent according to claim 4, wherein said fabric top cover includes marginal portions secured to said ribs in overlapping relation with the upper end of said fabric side wall.

7. A unitary collapsible tent comprising a plurality of normally straight flexible ribs each in-

cluding a pair of opposed slats, elongated fabric side wall sections having their opposed longitudinal edges secured to the ribs in overlapped relation between the slats, a top circular fabric cover having adjacent marginal portions with the opposed edges thereof secured between said slats in superposed relation to the adjacent ends of said side wall sections, and toggle link connections between adjacent ribs intermediate the ends thereof for flexing said ribs into spaced relation and drawing said side sections and top marginal portions taut in the erection of the tent.

VERNE ANDERSON.
